ANTENNA MOUNTING

Milton R. Friedberg, Cleveland Heights, Ohio, assignor to The Gabriel Company, Cleveland, Ohio, a corporation of Ohio

Application April 19, 1947, Serial No. 742,637

2 Claims. (Cl. 287—21)

1

This invention pertains to radio antennae for motor vehicles and the like and, more particularly, to a radio antenna having an adjustable articulated connection to its supporting base.

An object of the invention is the provision of a new and novel articulated connection between a radio antenna, which may be of the so-called whip type, and a mounting or supporting base adapted to be mounted at desired positions on the body of an automotive vehicle or the like, which connection is simple in structure, economical to manufacture, attractive in appearance, adjustable to a maximum amount, easily tightened in any adjusted position, and, when once tightened, shakeproof and rattleproof under even the most severe operating conditions.

Another object of the invention is the provision of a new and improved articulated joint or connection for permitting relative adjustment between a radio antenna and its supporting base, the joint having tightening means, and other means for deforming or indentation into at least one of the opposing surfaces of the joint upon tightening of the tightening means and for permanently fixing the joint in any adjusted position and preventing loosening or rattling thereof.

Another object of the invention is the provision of a new and improved articulated joint or connection for permitting relative angular adjustment between a radio antenna and its supporting base, the joint having means for tightening same, one of the members forming the joint having a projection of material harder than the material of another member of the joint which is adapted to be forced into the latter member upon tightening of the tightening means for relieving the tightening means of the principal stresses tending to loosen the joint when in use.

Another object of the invention is the provision of a new and improved combination of a radio antenna and supporting base therefor having an articulated joint or connection for permitting relative adjustment therebetween, the joint having tightening means, and other means supported on one of the members forming the joint for indentation into a surface of another member forming the joint upon tightening of the tightening means for permanently fixing the joint in any adjusted or desired position.

Another object of the invention is the provision of a new and improved combination of a radio antenna and supporting base therefor having an articulated connection therebetween

2

for permitting angular adjustment of the antenna relative to the base, the articulated connection comprising a ball member, a mating socket member, and tightening means for moving the members into opposed fixed relationship, one of the members having a projection harder than the material of the other member for deforming same upon tightening of the tightening means.

Another object of the invention is the provision of a new and improved radio antenna of the elongated whip type and a supporting base therefor having an articulated connection therebetween permitting adjustment of the antenna relative to the base, the connection comprising a ball member, a mating socket member, and a rotatable threaded tightening nut for tightening the connection, the member connected to the antenna having a projection extending beyond its mating surface generally on the axis of the antenna and of a material harder than the material of the mating member for being forced into same upon rotation and tightening of the nut, the arrangement being such that any tendency of the member connected to the antenna to rotate upon rotation of the nut also tends to rotate the projection on the axis of the antenna and into the other member at only a single position.

The invention resides in certain constructions and combinations and arrangements of parts, and further objects and advantages will be apparent to those skilled in the art to which it relates from the following description of the preferred embodiment described with reference to the accompanying drawing forming a part of this specification, and in which:

Fig. 1 is a side view partly in section showing a radio antenna and base embodying the present invention; and

Fig. 2 is an exploded view partly in section of portions of Fig. 1.

Generally speaking, the invention comprises a radio antenna and base therefor having an articulated connection therebetween so as to permit angular adjustment of the antenna relative to the base, the structure of the articulated connection being such that when the antenna is adjusted to its desired and final angular position relative to the base and the articulated connection is tightened, the members of the connection are so deformed as to prevent loosening under even the most adverse and severe conditions.

Referring to the drawings, the invention is shown as embodied in a radio antenna A of the

so-called whip type mounted or supported at its lower end on a supporting base B, in turn mounted or suitably positioned on the sloping panel C, of an automotive vehicle body or the like.

The panel C shown may be any portion of an automotive vehicle body or the like, whether sloping, vertical, or horizontal, or at the front or rear thereof, and is preferably perforated or drilled to provide a suitable opening (not shown) for passing a lead-in connection from the antenna A on the exterior of the panel to the interior thereof as well as a passage for clamping means to fasten the base B onto the panel.

As shown, the base B comprises a socketed member 10 and a pair of hollow cylindrical sleeves, an inner or lower sleeve 11 and an outer or upper sleeve 12, positioned on opposite sides of the body panel C with the ends thereof in abutment thereagainst. The central openings of the sleeves are preferably aligned with each other and with the opening in the body panel. The socketed member 10 may be positioned on the outer or upper end of the outer sleeve 12 and insulated therefrom by a suitable insulating washer 13. The socketed member 10, as shown, is electrically connected to the antenna A, and a threaded bolt 15 threaded into its lower surface extends through the aligned openings to the lower or inner side of the body panel C where it is suitably engaged by other threaded means (not shown) to firmly hold the sleeves 11, 12 in abutment with the body panel C and the socketed member in position on the outer sleeve 12.

The antenna A may take any one of a number of different forms and may be made of any desired metal. As shown, the antenna comprises a lower rodlike member 16 preferably of tubular construction and an upper rodlike member 17 also preferably of tubular construction of a smaller diameter than and telescopically arranged with the lower member.

In the embodiment shown, the lower end of the outer or lower tube 16 is provided with a ball member 18 which fits into a generally hemispherically shaped recess 19 in the upper surface of the socketed member 10, thus providing an articulated joint between the antenna A and the base B. The ball member 18 may be fixed to the antenna A in any suitable manner, but in the embodiment shown is provided with an axial boss 21 extending into and fitting snugly with the interior of the lower end of the lower or outer tube 16. As shown, the boss 21 has one or a plurality of spaced circumferentially extending grooves 22 in its surface into which adjacent portions of the wall of the lower tube 16 have been spun as at 23, thus providing a firm and indestructible connection between the antenna A and the ball member 18. The outer surface of the boss 21 has short, axially-extending, circumferentially-arranged serrations or knurls 24 on its outer surface which, when the boss is inserted into the interior of the tube 16 upon assembly, tend to bite through any film, rust, or scale on the interior of the tube 16 and provide a good electrical connection between the antenna and the ball member.

The ball member 18 may be held in assembled relationship in the hemispherical recess 19 of the socketed member 10 by any suitable means, but as shown in the drawings the outer surface of the portion of the socketed member 10 defining the recess 19 is threaded as at 26 and a sleeve nut 27 having at one end a radially inwardly extending flange 28 defining an opening 29 of

less diameter than the diameter of the ball member 18 is threadably engaged therewith. While the flange 28 may have a curved surface for engaging the surface of the ball member 18, it is preferred that the surfaces thereof intersect to form a relatively sharp or angular corner 30 for providing only a line contact with the surface of the ball member 18. Thus it will be seen that the antenna A may be tilted within the limits of the structure through a large number of angles relative to the socketed member 10 and the base B whereby the same antenna and base may be used on a plurality of different styles and/or makes of automotive vehicles, and the antenna A may be tilted to the angle most pleasing to the eye for the particular vehicle on which installed.

On antennas of the type referred to, because of the length of the antenna, the wind pressures imposed thereon at high speeds and vibrations of the automotive vehicle body due to irregularities in the pavement, etc., very high and severe stresses are imposed on the articulated connection. The present invention contemplates means for relieving the sleeve nut 27 and the normal frictional forces, when the joint is tightened, between the surfaces of the ball member 18 and the hemispherical recess 19 of much of the burden of resisting the forces on the connection. Thus, in the embodiment shown, the ball member 18 has a recess 31 preferably axially aligned with the boss 21 in which a pin 32 is inserted of a length such that a pointed end 33 will project beyond the surface of the ball member 18. The material of the pin may be harder than the material of the mating member, which in this instance is the socketed member 10, such that as the sleeve nut 27 is tightened down upon the final installation of the antenna, the pointed end of the pin 32 will perforate or indent into the surface thereof. Preferably the material of the opposed mating member is of relatively soft material such as brass, while the pin is of hardened steel or the like. The pin when imbedded in the opposing member provides broad bearing surfaces for absorbing the forces on the connection which will not pound out during severe usage.

With the construction shown, the antenna A is first adjusted angularly relative to the base B to any desired position and the sleeve nut 27 is then tightened down using a wrench or otherwise forcing the members into engagement and indenting or perforating the pointed end 33 of the pin 32 into and below the surface of the hemispherical recess 19.

It will be appreciated that when an installation is made, the base B will ordinarily first be securely mounted on the body panel C, with its axis adjusted as desired by positioning the angular faces of the sleeves 11, 12. The antenna A is then held manually or otherwise in its desired angular position and the nut 27 tightened down. Because of the rotation of the nut 27, the antenna A and ball member 18 may also tend to rotate about the antenna's own axis as well as possibly attempting to shift its angular position. Because of the length of the antenna, holding it in the desired angular position will not be difficult, but because of its small diameter, preventing it from rotating will be relatively difficult. With the construction shown, however, rotation of the antenna A about its own axis as the nut 27 is tightened will not be detrimental for the pointed end 33 of the pin 32 is, as stated, preferably positioned on the diameter of the ball member 18

coextensive with the axis of the antenna. Accordingly, rotation of the antenna A and the ball member 18 about the axis of the antenna and the pin 32 actually serves to increase the ease with which the pointed end 33 will be indented or perforated into the surface of the recess 19. By holding the antenna in its desired angular position as the nut 27 is first tightened, the first indentation of the pointed end 33 will be sufficient to maintain the antenna A in that angular position during subsequent tightening of the nut 27.

In the embodiment of the invention which has been described, the ball member 18 has been referred to as fixed to the base of the antenna and the socketed member 10 as forming a part of the base B. As an alternative construction, the socketed member could be suitably fixed to the antenna A and the ball member suitably fixed to the base B. In the case of such an alternative construction, it would be preferred that the pin 32 then be inserted in an aperture in the socketed member with the point of the projection on the axis of the antenna so that as the sleeve nut 27 is tightened and the antenna rotates about its axis, the pointed end 33 of the pin 32 will only tend to be driven into a single position in the opposed ball member. The pin may, if desired, be mounted on the member fixed to the base.

Thus it will be seen that an embodiment of the invention has been described which accomplishes the objects hereinbefore enumerated and others and provides an articulated connection for positioning an antenna relative to its base, which is easily assembled, and which when once assembled will remain relatively rattleproof throughout the life of the installation.

Although in accordance with the provisions of the patent statutes this invention is described as embodied in concrete form and structure and the principle thereof has been described together with the best mode in which it is now contemplated applying that principle, it will be understood that the apparatus shown and described is merely illustrative and that the invention is not limited thereto, since alterations and modifications differing materially in appearance and

structure will readily suggest themselves to persons skilled in the art without departing from the true spirit of this invention or from the scope of the annexed claims.

Having thus described my invention, I claim:

1. In a device of the type described including a base adapted to be mounted on the body of an automotive vehicle, an antenna, and means including a ball member and mating socket member for articulately supporting said antenna on said base; means for locking said members in any articulated position, one of said members having a recess with a pointed pin fixed therein and projecting therefrom for insertion into the surface of the other of said members upon locking said members in an adjusted position.

2. In a device of the type described including a base adapted to be mounted on the body of an automotive vehicle, an antenna, and means including a ball member and mating socket member for articulately supporting said antenna on said base; means for locking said members in any articulated position, one of said members having a recess with a pointed pin fixed therein and projecting therefrom for insertion into the surface of the other member upon actuation of said means for locking said members for permanently fixing said members in any adjusted position, said recess being formed in the member connected to said antenna and aligned with the axis of said antenna.

MILTON R. FRIEDBERG.
